Dec. 1822

William Craig, of Brooklyn, New York.

Letters Patent No 1822-Dated Oct 6th 1863.

Design for a Gas Cooking Stove.

The schedule referred to in these Letters Patent and making part of the same.

To all whom it may concern:

Be it known, that I, William Craig, of Brooklyn, in the County of Kings and State of New York, have invented or produced a new and ornamental design for a Gas Cooking Stove; and I do hereby declare that the following is a full and exact description thereof, reference being had to the accompanying drawing which forms a part of this specification and which is a front elevation of the stove complete, with a portion of the hose through which the gas is supplied, but without any of the vessels in which the cooking is to be effected.

X, X, are the legs and A, is the body of my stove and B, C, are two equal elevated parts constructed on A,

Dec. 1822

to support two kettles or other vessels for cooking. Similar beads b and c , and similar grooves b' and c' are produced on B and C , in the positions represented. B and C are rims which overhang or project on all sides as represented and all the members of these elevated parts B and C are circular.

The bead a and the groove a' extend around the body A in the position represented. A', A^2, A^3 are series of holes formed and located as represented and A^4 and A^5 are drooping rims or capitals and base which project in the manner represented A^4 at the top and A^5 at the bottom of the body A . All the members of $\dots \dots \dots A$ are semi-circular at the ends, but from the red line S, S , to the red line T, T , all said members are straight, both on the front and rear face. I perforate the capital A^4 with equidistant large holes A^6 , as represented.

The rear is like the front and one end like the other of the entire structure except for the double cock and connections now to be described.

D is a central flange or neck; E and F , are similar globular bodies, and e , and f , are similar ornamental handles formed on the plugs of the double cock. These are all on the front of the body A , and are connected with the works on the interior thereof by the rigid pipes M, N . The faces of each handle e , and f , are all alike:— the edges or ends e^1, e^2 , and f^1, f^2 , being scroll-formed, the central part e^3 and f^3 crown-like, and the top of each e^4, f^4 being plume-like, or grooved in a direction nearly radial from the centre of each handle, all as represented.

I prefer to make the double cock D, E, F , and the handles e, f , of brass or to cover them with a material resembling brass.

Having now fully described the exterior of

3

my Gas Cooking Stove, what I claim and desire to secure by
Letters Patent as my new and original design is as follows:

I claim the combination and arrangement
of ornamental figures and forms represented on the ac-
companying drawings forming together the ornamental
design for a Gas Cooking Stove.
